UNITED STATES PATENT OFFICE.

WILHELM REISMANN, OF VIENNA, AUSTRIA-HUNGARY.

APPARATUS FOR VAPORIZING MEDICAMENTS.

1,069,980.

Specification of Letters Patent. Patented Aug. 12, 1913.

Application filed November 7, 1912. Serial No. 730,016.

To all whom it may concern:

Be it known that I, WILHELM REISMANN, a subject of the Emperor of Austria-Hungary, residing at Vienna, Austria-Hungary, have invented certain new and useful Improvements in Apparatus for Vaporizing Medicaments, of which the following is a specification.

The present invention relates to improvements in apparatus by means of which medicated vapor may be employed for treating the mucous coating of the bronchial ways. An important and well recognized method of treating affections of such ways includes applying a medicament in finely divided condition to such coatings by inhalation. Heretofore it has been customary, when the desired medicament was of a solid nature, to prepare a solution therefrom, and then by suitable means vaporize this solution so that it could be readily inhaled. This method is however not entirely satisfactory or suitable for all conditions. By it there are obtained relatively large drops or particles which cannot thoroughly penetrate the bronchial ways and further, because of the large amount of moisture contained in the vapor, there is danger of catching a cold.

It has been proposed to apply finely divided solid medicaments directly to the parts to be treated as by forcing pulverized material through a very fine mesh screen, but by this method it has been impossible to obtain particles of such fineness that all portions of the mucous coatings would be reached thereby.

The object of the present invention is to provide means by which solid medicaments may be vaporized and the vapor, in a dry condition free from moisture, caused to intimately penetrate the finest ramifications of the bronchial ways to be treated.

In the accompanying drawings, Figure 1 is a vertical sectional view through an apparatus constructed in accordance with the present invention; Fig. 2 is a plan view; Fig. 3 is a horizontal sectional view, substantially on the line A—A of Fig. 1; Figs. 4 and 5 illustrate in vertical section and plan another embodiment or modification of the invention.

Referring to the drawings, and particularly to Figs. 1 to 3, it will be seen that the apparatus comprises a housing or casing *a* which is preferably provided with a covering of heat insulating material and is sup-

ported upon suitable legs or standards, three, *i*, *j*, *k*, being shown in the embodiment of the invention illustrated in the figures referred to. Within this housing or casing is 60 suitably supported a crucible *c* adapted to receive the medicament to be vaporized. As shown the crucible *c* is supported by a plurality of adjusting screws *e*, *f* and *g*. The adjusting screws *e*, *f* and *g* are surrounded by porcelain insulating tubes. A slit *h* is provided in the casing wall so that one of the screws *e* may be adjustable therein and permit the ready removal of the parts. Above the crucible is arranged a bent 70 vapor discharge conduit *d* which extends in an upwardly inclined direction laterally through a side wall of the casing and has its lower inner end positioned to receive vapor rising from the crucible. This conduit *d* is 75 preferably made of porcelain. Experience has shown that such material is best adapted for this purpose. Tubes of metal are undesirable both because of the fact that they readily become highly heated and also because they are liable to be deleteriously affected by the action of the medicament, for example hydrochlorate of soda which is employed. Conduits of meerschaum or similar material are also unsuited for use by reason 80 of their being liable to be injured by the action of the vaporized medicament. The crucible *c* can be made of platinum or other suitable material. Beneath the housing or casing *a*, which, as shown, has a downwardly tapering bottom *b*, is arranged a suitable heater or burner such as conventionally illustrated at *p* in Fig. 1, the upper end of which is beneath a central opening in the bottom of the housing *a*. Through 90 the top of the housing *a* extends an outlet *q* for the products of combustion. Means are provided whereby a stream or body of gas under pressure is caused to move through the discharge conduit *d* to carry the vapor 100 rising from the crucible *c* to the mouth of such tube, where they may be inhaled by a patient. In the embodiment of the invention illustrated in Fig. 1, the leg *k* is made of tubular form and constitutes the conduit 105 through which the gas for the purpose stated is conducted. This leg is provided near its lower end with a lateral inlet *m* and with two discharge or outlet branches *n*, *o*, the former opening into the lower portion 110 of the casing *a* so as to assist combustion of the burner *p*, and the branch *o* extending

upwardly and laterally into the rear end of the vapor conduit *d*. Any suitable gas may be employed. For many purposes compressed air supplied to the inlet *m* from any suitable means as from a hand bulb or bellows, will be found satisfactory.

In the modification of the invention illustrated in Figs. 4 and 5, the shell *n* is provided with an interior body of asbestos or other suitable heat insulating material *s*, and the crucible *c* is embedded in a block *t* in which is also embedded an electrical heating coil *u* having suitable terminals *v*, *w*. In this form of the invention the gas for transporting the vapors arising from the crucible is introduced into the bent discharge conduit *d* by a substantially horizontally arranged inlet pipe *y* that extends across the interior chamber *x* within the upper portion of the casing and into the bend of conduit *d* above the mouth of the crucible. If preferred instead of compressed air some other form of gas, as for example nitrogen or oxygen, may be utilized to convey the vapors in the tube *d*.

The outer end of the vapor discharge conduit *d* may, in each case, be inclosed within a suitable hood *z*, as shown in Fig. 1.

The manner of operating and the advantages incident to the apparatus herein described will be readily understood and appreciated. It is particularly adapted for using solid medicaments such as ordinary salt which has been found very beneficial in the treatment of diseases or unnatural conditions of the coatings of the bronchial ways.

Having thus described the invention what is claimed is:

40 1. In an apparatus for vaporizing medicaments, the combination of a crucible, means for heating the crucible, a conduit adapted to receive vapor rising from the

crucible and having its discharge end deflected laterally, and means for supplying 45 gas under pressure to said conduit to move across the top of the crucible toward the laterally deflected discharge end thereof.

2. In an apparatus for vaporizing medicaments, the combination of a crucible for 50 containing a medicament, means for heating the crucible to vaporize the contents thereof, an inclined conduit having its inlet end arranged above the crucible to receive vapor rising therefrom and its upper 55 discharge end beyond the side of the crucible, and a pipe for admitting gas under pressure into said conduit adjacent its inlet.

3. In an apparatus for vaporizing medicaments, the combination of a housing or 60 casing, a crucible supported in said casing, a discharge conduit supported above the crucible with its inlet arranged to receive vapor rising from the crucible and its discharge extending through a wall of the casing, means for heating the crucible, and a pipe extending through a wall of the casing 65 into the discharge conduit for supplying gas under pressure thereto.

4. In an apparatus for vaporizing medicaments, the combination of a crucible, a discharge conduit having its inlet communicating with the crucible, a burner for heating the crucible, and a conduit for gas under pressure having two lateral branches, 75 one terminating adjacent the burner and the other extending into the discharge conduit to force the vapor rising from the crucible therethrough.

In testimony whereof I affix my signature in presence of two witnesses.

WILHELM REISMANN.
